UNITED STATES PATENT OFFICE.

GEORGE F. ATWOOD, OF EAST ORANGE, NEW JERSEY, ASSIGNOR TO WESTERN ELECTRIC COMPANY, OF CHICAGO, ILLINOIS, A CORPORATION OF ILLINOIS.

TELEPHONE-TRANSMITTER.

No. 902,043.

Specification of Letters Patent.

Patented Oct. 27, 1908.

Application filed March 12, 1906. Serial No. 305,549.

To all whom it may concern:

Be it known that I, GEORGE F. ATWOOD, citizen of the United States, residing at East Orange, in the county of Essex and State of New Jersey, have invented a certain new and useful Improvement in Telephone-Transmitters, of which the following is a full, clear, concise, and exact description.

My invention relates to a telephone transmitter, its object being to provide a transmitter which will be capable of practical outdoor use, and wherein the terminals are located in position for convenient access thereto.

The transmitter of my invention was especially designed for military field use, where it will be subjected to hard usage, and be exposed to inclement weather.

One feature of my invention consists in the means which I employ to render the containing case water-tight. The opening in the front supporting plate is covered by a waterproof membrane held in place by the mouthpiece of the transmitter, which preferably comprises a perforated disk secured to the front supporting plate over the opening therein, said membrane being secured between said disk and plate. The two members of the case are preferably telescoped and clamped together by a clamping ring which covers the outer joint between said members. With this arrangement the transmitter is rendered thoroughly water-tight.

Another feature of my invention consists in the location of the instrument terminals so that ready access may be had thereto without disturbing the adjustments or connections. To this end I provide a terminal chamber upon the rear of the containing case in which said terminals are located, the chamber having a removable cap permitting free access to all the connections of the instrument. The rear wall of the containing case has a hole therein opening into the terminal chamber and through which the terminals of the instrument project.

When the transmitter is used in connection with local battery telephones, it is desirable to have the local battery circuit including the transmitter closed only while the instrument is in use, and a further feature of my invention consists in the switching mechanism within said chamber and controlled from the outside thereof, for electrically connecting the switch terminals of the transmitter when the instrument is desired for use.

I will describe my invention particularly by reference to the accompanying drawing wherein

Figure 1 is a front elevation of a transmitter embodying my invention; Fig. 2 is a vertical sectional view thereof; Fig. 3 is a rear view of the front supporting plate and the transmitter carried thereby; Fig. 4 is a rear view of the containing case of the transmitter and the terminal chamber mounted thereon with the cap of the chamber removed; and Fig. 5 is a detail sectional view on line 5—5 of Fig. 3.

Similar letters of reference designate like parts throughout the several views.

The front supporting plate *a* carries upon its rear side the working parts of the transmitter, said plate having a central opening *a'* therein before the diaphragm of the transmitter. A thin waterproof membrane *b*, preferably of rubber, covers the opening *a'*, being held in place by the mouthpiece *c*, which preferably comprises a perforated disk secured to the front plate over the opening therein, the membrane being held in place between the disk and the plate. Moisture is thus prevented from reaching the transmitter through said opening.

The front supporting plate *a* is provided at its rear with an inclosing member *d*, which is preferably cup-shaped, said parts *a* and *d* being united by a telescopic joint and locked in place by a ring *e* which seals the joint. The plate *a* is provided with a rearwardly extending annular flange *a'*, which fits within the member *d*, until the outwardly-projecting annular lug or flange *a* carried by the plate abuts against the edge of the member *d*. The clamping ring is internally threaded and is adapted to screw upon the member *d*, said ring having an inturned annular lip *e'* adapted to engage said lug *a*, thereby locking the parts *a* and *d* in position and sealing the joint between them to prevent moisture from entering the case at such point.

An auxiliary support is provided for the transmitter in the form of a bridge piece *f* secured at the rear of the plate *a*, upon the inturned lips *a* and *a'* formed from the annular flange *a*.

The rear member *d* of the inclosing case carries on its outer surface a chamber *g* in which are located the terminals of the instrument. The member *d* has an opening *d'* therein through which the insulated termi-

nals of the transmitter carried by the bridge *f* project into the chamber *g*, said terminals being preferably mounted upon an insulating block *h*, secured to said bridge. The flange 5 *a*² has a slot *a*⁵ therein which is adapted to receive a pin *d*² carried upon the inner surface of the member *d* to prevent turning of the plate *a*. Said chamber *g* also contains the switch terminals *i i* of the transmitter, said 10 terminals being mounted upon the wall of the chamber but insulated therefrom. In practice one of said switch terminals may be connected with one terminal of the transmitter, the other switch terminal being connected 15 with one pole of the local battery, while the other transmitter terminal would be connected with the other pole of the battery, said circuit, of course, including the primary winding of an induction coil. Thus when 20 the switch terminals are electrically connected, the local circuit of the transmitter is completed.

I provide switching mechanism within the chamber adapted to be operated from the 25 outside thereof for connecting said switch terminals when the transmitter is desired for use. Each switch terminal is connected with a spring *k*, said springs being adapted to be engaged and connected by a spring-restored 30 plunger *l* projecting through the wall of the chamber. The terminals are thus located in position for ready access without disturbing the adjustment of the transmitter. A removable cap *m* is provided for the chamber 35 permitting access to said chamber. Conductors may be led to said terminals through a tube *n* communicating with an opening in the wall of the chamber.

I claim:

- 40 1. The combination with a telephone transmitter, of a containing case therefor, a chamber secured to the rear wall of the case, said wall having a hole therein opening into said chamber, and an insulated block carrying the transmitter terminals projecting through said opening into said chamber.
- 45 2. The combination with a telephone transmitter, of a front supporting plate for supporting the working parts of the transmitter, an auxiliary support for the transmitter carried by the plate behind the transmitter, insulated terminals for the transmitter carried by said support, a cup-shaped member secured to the rear of said plate, a 50 chamber upon the outer surface of said member, and a removable cap for said chamber, the terminals carried by said support projecting through an opening in said cup-shaped member into said chamber.
- 55 3. The combination with a telephone 60 transmitter, of a front supporting plate having a rearwardly extending flange, a bridge piece at the rear of the transmitter, inwardly projecting lips formed from said flange and supporting said bridge piece, an insulated block mounted upon said bridge piece and carrying the transmitter terminals, a cup-shaped member within which the flange of the front plate fits, means for securing said plate and member together to form an in-

closing casing for the transmitter, and a terminal chamber mounted upon the rear of said cup-shaped member, said member having an opening therein through which said block projects into said chamber.

4. A containing case for telephone transmitters comprising a front supporting plate having a rearwardly-extending annular flange, a cup-shaped member in which said flange fits, an outwardly projecting annular lug carried by said plate abutting against the edge of said cup-shaped member, said member having screw threads upon its outer surface, an internally threaded clamping ring screwing upon said cup-shaped member, and an inturned annular lip carried by said ring and abutting against said outwardly projecting lug, whereby said cup-shaped member and front plate are locked together and the joint between said parts sealed.

5. The combination with a telephone transmitter, of a containing case therefor, a chamber secured to the rear wall of the case, said wall having a hole therein opening into said chamber, an insulated block mounted within said containing case, transmitter terminals mounted on said block and projecting through said opening into said chamber, and a spring-pressed plunger passing through the side walls of said chamber and arranged to control the connection of said switch terminals.

6. The combination with a telephone transmitter, of a containing case therefor, a chamber secured to the rear wall of the case, said wall having a hole therein opening into said chamber, an insulated block mounted within said case, transmitter terminals mounted on said block and projecting through said opening into said chamber, a pair of springs connected with said terminals, and a plunger passing through the wall of said chamber and arranged when operated to connect said springs.

In witness whereof, I, hereunto subscribe my name this 3rd day of March A. D., 1906.

GEORGE F. ATWOOD.
